CLAIM

The ornamental design for a wheel-chair, as shown and described.

DESCRIPTION

FIG. 1 is a front perspective view of a wheel-chair showing my new design;

FIG. 2 is a side elevational view thereof, the opposite side elevational view being a mirror image of that shown;

FIG. 3 is a front elevational view thereof;

FIG. 4 is a rear elevational view thereof;

FIG. 5 is a top plan view thereof;

FIG. 6 is a rear elevational view thereof.

*FIG. 1**FIG. 2**FIG. 3*

FIG. 5
